UNITED STATES PATENT OFFICE.

DANIEL D. STETLER, OF MEDFORD, OKLAHOMA TERRITORY.

DESIGN FOR A MEMBER FOR FENCE-TOOLS.

SPECIFICATION forming part of Design No. 30,281, dated February 28, 1899.

Application filed January 12, 1899. Serial No. 701,993. Term of patent 14 years.

To all whom it may concern:

Be it known that I, DANIEL D. STETLER, a citizen of the United States, residing at Medford, in the county of Grant and Territory of Oklahoma, have invented a new and useful Design for a Member for a Fence-Tool, of which the following is a specification.

My invention relates to designs for a member for a fence-tool, which is illustrated in the accompanying drawings, in which—

Figure 1 is a perspective view of the design for the member of a fence-tool embodying my invention, the coöperating member shown in dotted lines. Fig. 2 is a central longitudinal view of the same. Fig. 3 is a cross-sectional view taken on line 3 3 of Fig. 1.

My design consists of a handle A, having the two parallel projecting jaws b. The outer ends of these jaws are curved, as shown at e, each jaw being provided with a transverse slot or opening d, passing transversely

through its outer face, one of the openings having straight walls and the other a curved wall, as illustrated.

The essential feature of my design consists in a handle having an enlarged end having the two parallel jaws with curved outer ends, the upper and inner ends of the curved jaws being provided with downwardly-projecting openings, as illustrated.

Having thus described my invention, what I desire to secure by Letters Patent is—

The design for a member of a fence-tool, substantially as herein shown and described.

In testimony whereof I have hereunto set my hand in the presence of two subscribing witnesses.

DANIEL D. STETLER.
